UNITED STATES PATENT OFFICE.

GEORGE N. BLANCHARD, OF SAN FRANCISCO, CALIFORNIA, ASSIGNOR TO COLMAR BURNER CO., INC., OF SAN FRANCISCO, CALIFORNIA, A CORPORATION OF CALIFORNIA.

BURNER ATTACHMENT.

1,381,273.

Specification of Letters Patent. Patented June 14, 1921.

Application filed April 21, 1920. Serial No. 375,440.

To all whom it may concern:

Be it known that I, GEORGE N. BLANCHARD, a citizen of the United States, residing at the city and county of San Francisco and State of California, have invented certain new and useful Improvements in Burner Attachments, of which the following is a specification.

The present invention relates to an apparatus for heating and igniting a suitable hydrocarbon fuel generator; one which is automatically controlled by a predetermined temperature, whereby gas for heating and igniting the generator is generated for a given period and is automatically ignited, and is then extinguished at the termination of this predetermined period.

The principal object of the present invention is to provide an apparatus of the above type, whereby the operator after starting the same may leave it unattended with the assurance that a sufficient quantity of gas will be generated and automatically ignited to raise the temperature of the main fuel generator to a given point and thence ignite the gas issuing therefrom, and after these operations will automatically shut off without any danger of flooding or operating for more than the predetermined or required time.

With the above mentioned and other objects in view, the invention consists in the novel construction and combination of parts hereinafter described, illustrated in the accompanying drawings, and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Figure 1 is a longitudinal sectional view of one form of burner illustrating my improved apparatus positioned in operative relation with the burner generator.

Fig. 2 is a vertical sectional view taken on line 2—2 of Fig. 1, viewed in the direction of the arrows.

Fig. 3 is a transverse sectional view taken on line 3—3 of Fig. 2, viewed in the direction of the arrows.

Fig. 4 is a view in side elevation of my improved apparatus, partly in section, the section being taken on line 4—4 of Fig. 2.

Fig. 5 is a vertical sectional view taken through the center of the stove on line 5—5 of Fig. 2.

Fig. 6 is a broken sectional view taken on line 6—6 of Fig. 5, illustrating the channels controlled by the thermostatic valve.

Referring more particularly to the several views of the drawings, wherein like characters of reference designate corresponding parts—1 indicates any conventional form of hydrocarbon burner formed with a suitable air inlet 2 and the pilot 3 burner opening 3.

Disposed above the burner 1 and extending parallel with the pilot burner opening 3 is a suitable generator 4, within which is generated any suitable hydrocarbon fuel gas 5 which discharges from the tip end 5 thereof into the main burner 1.

Hydrocarbon fuel is fed to the generator through the valve controlled feed pipe 6, connected to any suitable source of fuel supply, and the gas discharging from the tip 5 is adapted to be controlled by a suitable needle valve 7 disposed longitudinally within the generator 4.

Disposed parallel with the generator 4, slightly below and at one side thereof and of a length corresponding to that of the generator 4, is a suitable tubular member or torch 8 provided in its surface, adjacent said generator 4, with a line of perforations 9, those at the terminal end of the torch being preferably larger than those adjacent the base of the torch. The torch is supported at its rear end by the plate 10, through which it passes, and which is secured to an arm 11 extending upwardly from the rear of the burner 1. Threaded into the rear open end of the torch 8 is a suitable chambered member 12 provided with a discharge opening 13 disposed centrally of the rear end of the torch 8 and a lateral opening 14 connected with one end of a suitable generating pipe 15. The rear open end of the chambered member 12 is closed by a suitable plug 16 threaded thereinto; Fig. 4 of the drawings.

Mounted at one side of the rear end of the torch and supported by the plate 10 is a suitable cylindrical shell 17 open at its top and bottom, and over the top, in 110

spaced relation to the upper open end thereof, is held a suitable cover 18. Beneath the shell 17 is held a suitable circular burner 19 of any wick material, such as fabric or asbestos, and the fuel is supplied to this burner through a feed pipe 20, at the outer end of which is secured a suitable receptacle 21 having an open top 22 and which is adapted to receive a quantity of fuel, preferably wood alcohol.

Extending transversely through the upper end of the shell 17 and secured at its inner end to the plate 10 by the nut 23 is a suitable, relatively thin tube 24 for containing a body of fluid 25, such as mercury, and about that portion of the tube 24 within the shell 17 is coiled a portion of the relatively small pipe 15, the remainder of which is coiled circumferentially in spirals within 20 the shell 17 and above the burner 19, with its terminal portion extending without the shell 17 at its lower edge, as at 26. The rear end of the tube 24 is enlarged as at 27 and within the same is received a flexible closure plate 28 which confines the fluid 25 within the tubular portion 24. The plate is held in position by a collar 29 threaded into the enlarged rear end 27 of the tube 24, and said collar is in turn closed by a suitable body 30, threaded thereinto and provided with an opening 31 extending therethrough in line with the chamber of the tube 24.

Mounted within the recess 32, formed by the collar 29 and body 30, is a suitable piston 33, the head 34 being held in contact with the plate or diaphragm 28 by a coiled spring 35 positioned between the underside of the head 34 and the wall of the body 30 surrounding one end of the opening 31. The outer end of the body 30 in line with the opening 31 therethrough is chambered, said chamber being closed by a plug 36, chambered as at 37, and in said chamber 37 is adapted to reciprocate a tapered valve 38 having adjustable connection with the stem 33 of the piston. The valve 38 is adapted for controlling the communication between the interior of the channel 31 and the chamber 37, and the adjustment of the valve relatively to the piston controls the operation of the valve in accordance with different temperatures of the fluid 25. The body 30 is provided with a lateral fuel feed opening 39 communicating at one end with the channel 31 and with which is connected a pipe 40 leading from a T 41 in the fuel feed pipe 6, thus fuel is fed through the pipe 40 into the channel 31. The terminal portion 26 of the generator pipe 15 communicates 60 with the chamber 37 through intersecting channels 41, and thus the flow of fuel from the pipe 40 into the pipe 26 is controlled by the operation of the valve 38 which is actuated in accordance with the temperature 65 of the fluid 25 in the tube 24, which is in

turn controlled by the flame from the burner 19. To ignite the generated gas passing from the perforations 9 in the torch 8, I provide a conducting tube 42 open at its opposite ends, and at its inner end communicating with the interior of the shell 17 above the burner 19 through an opening 43 in the side wall of the shell. This end of the tube 42 is beveled, as in Fig. 3 of the drawings, and a suitable guide or directing plate 44 secured to the shell 17 at one side of the opening 43, extends into this beveled end of the tube 42, as in Fig. 3 of the drawings. The outer end of the tube 42 is opened for its full area and terminates slightly in rear of 80 the innermost perforation 9.

Extending radially from the torch 8 immediately in advance of the outer end of the tube 42 is a gas conducting and torch igniting tip 45, the lower end of which extends a short distance into the torch 8, as at 46, and is provided with a lateral opening 47 facing the discharge opening 13 in the plug 12. The upper end of the member 45 is closed by a plug 48 and is provided in its opposite side walls with registering openings 49 and 50, the opening 49 facing the perforations 9 and the opening 50 facing the discharge of the tube 42.

The device being assembled as in the drawings, the same operates in the following manner:—

The chamber or container 21 being filled with a quantity of fuel known to burn through the wick a predetermined period 100 and the valve of pipe 6 being opened and 7 closed, the wick 19 is ignited. The flame from the wick 19 completely fills the shell 17, heating the liquid in the tube 24, and at the same time heating the pipe 15 coiled 105 about the tube and within the shell 17. On the raising of the liquid 25 to a predetermined temperature dependent on the adjustment of the valve 38 on the stem 33, the valve 38 is opened, permitting fuel to pass 110 from the pipe 40 into the portion 26 of the pipe 15, which conducts the fuel into the coils within the shell 17. These coils being at a high temperature, the fuel in passing therethrough is readily gasified and discharges therefrom through the nozzle 13 into the torch 8. The flame from the burner 19, due to the draft within the shell 17 and the relative position and formation of the plate 44 and beveled end of the tube 42, ignites the gas, which is directed rearwardly through the tube 42 from the opening 50. The gas under pressure as delivered into the torch 8 through the opening 13 is directed toward the opening 47 and the open lower 125 end 46 of the igniting tube 45, and in passing upwardly through said tube 45 discharges through both openings 49 and 50. However, only the opening 50 is necessary, and the opening 49 may be dispensed with. 130

The gas discharged from the opening 50 rearwardly into the tube 42 is directed through the opening 43 in the shell 17 and is thus ignited by the flame within the shell, 5 causing what may be termed a back-fire in the tube 42, which, in turn, ignites the gas discharging from the perforations in the torch 8.

It will thus be apparent that all operations, after the igniting of the wick 19, are 10 automatic in generating the fuel for the torch and in igniting the torch. On the fuel 21 being consumed by the flame of the wick 19, the tube 24 becomes cooled, permitting 15 the valve 38 to seat and shut off the flow of fuel passing into the chamber 36. At such time as the torch 4 has become sufficiently heated, the valve 7 may be opened and the flame from the perforations of the terminal 20 end of the torch will ignite the gas passing from the burner tip 5 of the generator 4.

I claim:

1. An apparatus for the described purpose, the same comprising an elongated tubular torch provided in its side wall with a line of burner perforations, a shell positioned adjacent to one end of the burner, a pipe coiled within the shell and connecting at one end with the interior of the torch at 30 its rear end, a valve controlled chamber with which the opposite end of said pipe connects, a thermostat extended into said shell and adapted for operating the valve, a fuel feed pipe communicating with said chamber, and a burner associated with said shell.

2. An apparatus for the described purpose, the same comprising an elongated tubular torch provided in its side wall with a line of burner perforations, a generator 40 associated with the torch for generating gases for supplying thereto, a burner for heating the generator, means for automatically supplying fuel to the generator in accordance with the temperature of the generator, and 45 means for automatically igniting the gas issuing from said perforations by the flame from said generator burner.

3. An apparatus for the described purpose, the same comprising a torch provided 50 with a burner perforation, a shell positioned adjacent to said torch, a pipe within the shell and connected at one end with the interior of said torch, a valve chamber with which the opposite end of said pipe communicates, a fuel feed pipe communicating with said valve chamber, a valve for controlling the flow of fuel through the chamber, and means for heating the pipe within the shell for the purpose described.

60 4. An apparatus for the described purpose, the same comprising a torch provided with burner perforations, a shell positioned adjacent thereto, a pipe within the shell and connected at one end with the interior of 65 said torch, a valve chamber with which the

opposite end of said pipe communicates, a fuel feed pipe communicating with said valve chamber, means for heating the pipe within the shell, and a thermostatic operated valve associated with said chamber and controlled by the temperature within said shell for controlling the flow of fuel through the valve chamber.

5. An apparatus for the described purpose comprising an elongated tubular torch 75 provided in its side wall with a line of burner perforations, a shell positioned adjacent to the rear end thereof and formed in its side wall with an opening, a pipe coil within the shell and connected at one end 80 with the interior of said torch at its rear end, said pipe at its opposite end connecting with a valve controlled fuel supply, an open ended igniting tube extending longitudinally of the rear of said torch with one end 85 terminating adjacent to said shell side wall opening, and with its outer end terminating adjacent to the end of the line of burner perforations, a tubular member extending laterally through the side wall of said torch 90 adjacent to the outer end of said igniting tube and provided with openings facing both the interior of said igniting tube and said line of burner perforations, and a burner associated with said shell for heating 95 the same and for providing a flame for igniting the gas discharging into said igniting tube.

6. In combination with a tubular torch provided with a burner perforation, means 100 for supplying gas thereto, an open ended igniting tube associated with said torch, a connection extended from the said torch adjacent to the said burner perforation for supplying gas to the forward end of said 105 igniting tube and toward said perforation, and means for igniting the gas from the rear end of said igniting tube whereby a flame is provided adjacent to said burner perforation for igniting the gas issuing therefrom. 110

7. In combination with a tubular torch provided in its side wall with a line of burner perforations, a shell positioned adjacent to the rear end of said torch, a thermostatic tube extended transversely from said 115 shell, a pipe connecting at one end with the rear of said torch and coiled within said shell and about said thermostatic tube, a valve chamber to which the opposite end of said pipe connects, a valve within said chamber and operated by said thermostat for controlling the flow of fuel therethrough into said pipe, and a burner associated with the said shell for heating the interior thereof.

8. In combination with a main burner, a 120 generator associated therewith and normally heated thereby, a torch provided with a line of burner perforations and associated with the generator for preheating the same, means associated with the torch for generat- 125 130 135

ing gas therefor, means for automatically igniting the gas issuing from the torch burner perforations from said torch gas generator, means for supplying fuel to the torch generator to be generated into gas, and means for cutting off said fuel supply on the temperature of the generator falling below a predetermined degree.

9. An apparatus for the described purpose comprising a torch provided with burner perforations, a shell positioned adjacent to the rear end thereof, and formed in its side wall with an opening, a pipe within the shell and connected at one end with the interior of the torch at its rear end, said pipe at its opposite end connecting with a valve controlled fuel supply, an open ended igniting tube extending longitudinally of the rear of said torch with one end terminating adjacent to said shell side wall opening, and with its outer end terminating adjacent to one of the burner perforations, a tubular member extending laterally through the side wall of said torch adjacent to the outer end of said igniting tube and provided with an opening facing the interior of said igniting tube whereby gas from the torch is discharged rearwardly into said igniting tube, and a burner associated with said shell for heating the pipe therein and for igniting the gas discharging rearwardly into said igniting tube.

10. In combination with a torch provided with burner perforations, means for supplying gas thereinto, an open ended igniting tube disposed longitudinally of the rear of said torch, a connection extended from said torch adjacent to one of said burner perforations for supplying gas rearwardly through the forward end of said igniting tube, and means for igniting the gas from the rear end of said igniting tube whereby a flame is provided adjacent to said burner

perforations for igniting the gas issuing therefrom.

11. An apparatus for the described purpose, the same comprising a tubular torch provided with a burner opening, a shell, a pipe within the shell and connecting at one end with the end of the torch, a valve controlled chamber with which the opposite end of said pipe connects, a thermostat acted on by the heat of the shell and adapted for operating the valve, a fuel feed pipe communicating with the chamber and a heater associated with the shell.

12. An apparatus for the described purpose comprising a tubular burner heating torch provided with a burner perforation, a generator associated with the torch for generating gases for supplying thereto, a heater for the generator, means for automatically supplying fuel to the generator dependent on the temperature thereof, and means for automatically igniting the gas issuing from said perforation by the flame from said generator heater.

13. An apparatus for the described purpose, comprising a burner heating torch, a generator associated with the torch for generating gases for supplying thereto, a heater for the generator, and a thermostatic valve for controlling the supplying of fuel to the generator.

14. An apparatus for the described purpose, comprising a burner heating torch, a generator associated with the torch for generating gases for supplying thereto, a heater for the generator, a thermostatic valve for controlling the supplying of fuel to the generator, and means for automatically igniting the gas issuing from said torch.

In testimony whereof I have signed my name to this specification.

GEORGE N. BLANCHARD.
